UNITED STATES PATENT OFFICE.

ELMER E. LYON, OF HARRISONVILLE, MISSOURI

DEVICE FOR CHECKING THE ROCKING AND REBOUNDING OF VEHICLES.

1,385,565.

Specification of Letters Patent. Patented July 26, 1921.

Application filed December 8, 1918. Serial No. 342,086.

To all whom it may concern:

Be it known that I, ELMER E. LYON, a citizen of the United States, and resident of Harrisonville, county of Cass, and State of Missouri, have invented a certain new and useful Improvement in Devices for Checking the Rocking and Rebounding of Vehicles, of which the following is a complete specification.

10 The present invention pertains to vehicle spring devices and aims to provide an improved auxiliary spring mechanism, the operation of which will tend to reduce or check the rocking as well as the rebounding movement of the vehicle to which the improved mechanism is applied.

In carrying out the invention, I provide auxiliary spring devices adapted to be associated in connection with opposite sides of the vehicle body adjacent the opposite ends of the transverse supporting spring, and so arranged as not only to check any rocking tendency of the vehicle in either direction, but also to prevent any undue rebounding movement thereof.

It is also sought to provide a device of the character described which will add materially to the riding comfort of the vehicle, while incidentally reinforcing the action of the main rear vehicle springs and also reducing the danger of the vehicle over-turning on account of excessive rocking movement.

It is also sought to devise a simple, inexpensive and durable device of this character which will require no alteration in the vehicle to which the same is to be applied.

With these general objects in view the invention will now be described by reference to the accompanying drawing illustrating one form of construction which I have devised for embodying the improvement, after which the novel features will be defined in the appended claims:

15 In the drawing—

Figure 1 is a rear end view, showing a portion of a vehicle having applied thereto a set of spring devices embodying the present improvement;

20 Fig. 2 is a transverse section taken on the line 2—2 of Fig. 1;

Fig. 3 is a similar section, taken on the line 3—3 of Fig. 1;

Fig. 4 is an enlarged detailed view of the 55 Fig. 5 is a perspective view showing one of the spring supporting elements.

Referring now to the drawing in detail, this illustrates the improved mechanism as applied to the rear end of a vehicle comprising the rear axle housing 6, to which is connected in the usual manner the main rear supporting spring 7. On this transverse spring 7, is suitably mounted a channel member 8, whereby the spring 7 is connected to the vehicle body 9, the latter being secured to said channel member by means of a series of bolts 10.

Within each of the ends of said channel member is rigidly secured a bar 11, having a suitable bolt opening 12, whereby the same may be attached by means of one of the bolts 10, each of said bars 11, being secured in place with its inner end abutting against the next adjacent bolt 10. Each of the bars 11 also projects outwardly away from the end of the channel member 8, and laterally of the vehicle body 9, where the free end of each bar is provided with a hook portion 13, adapted for supporting engagement with the upper loop end 14, of a coil tension spring element 15. The lower end of the spring 15 is provided with a loop 16, extending at right angles to the loop 14, and adapted for supporting engagement with a strap 17. This strap 17 is of a suitable length adapted to span the distance between the lower end of the spring 15 and the axle 6, extending around the axle and astride the transverse supporting spring 7.

90 For the purpose of spreading the strap 17, and preventing the same from wearing engagement with the spring 7, a V-shaped stirrup 18 is provided, this stirrup being mounted within the loop 16, and embracing the strap 17, at opposite sides of said loop. The end portions of the stirrup 18 are formed with suitable lugs 19, adapted to engage the side edges of the strap and retaining the same in proper position on said stirrup. 100 The strap 17 is provided with a suitable buckle 20, whereby any slack in each of the spring devices may be initially taken up when applied to the car with the body 9, in normal upright position.

105 It will thus be apparent that I have pro-

vided a simple, durable and efficient device for carrying out the desired objects of the invention, and one which requires no cutting or punching in order to apply the same in 5 its operative position, the device simply requiring the loosening of a pair of bolts 10, to secure the same in place with the strap 17, embracing the adjacent end of the axle 6, and extending on opposite sides of each end 10 of the transverse spring 7. It will be readily understood that any undue rebounding of the vehicle will be promptly checked, and at the same time any excessive rocking movement of the vehicle body will likewise be reduced to such an extent as to practically eliminate any liability to accident, such as overturning, from this cause. Incidentally, the spring 7, is relieved of a great deal of its strain, thus materially lengthening the 20 life of this spring, as well as that of the car on account of the shocks which are eliminated, and to which the car is otherwise subjected. There is practically no wear on the parts of the device, it being apparent that 25 the stirrup 18 spreads the strap 17, and retains the same entirely out of engagement with the transverse spring at all times. The device is entirely free from complications and may be easily and quickly attached in 30 position by any unskilled person. Obviously, the use of the device also adds greatly to the ease and riding comfort of the car, and while the device is particularly suitable and desirable in connection with small 35 sedans and touring cars, it is apparent that the same would be equally desirable and effi-

cient if applied in the same manner to small delivery vehicles, such as laundry, bread and grocery trucks.

While I have illustrated what I regard as 40 the preferred form of construction, I desire to reserve the right to make such changes as may fairly fall within the scope of the appended claims.

What I claim is:

1. The combination with a vehicle body, axle and transverse supporting spring, of a bar secured rigidly to said body and projecting laterally therefrom, a coil tension spring carried by the outer end of said bar, 50 a strap looped around said axle and connected tautly with the lower end of said coil spring, and a spreader device associated with said strap and coil spring for maintaining said strap out of engagement with 55 said transverse spring.

2. The combination with a vehicle body, axle and transverse supporting spring, of a bar secured rigidly to said body and projecting laterally therefrom, a coil tension 60 spring carried by the outer end of said bar, a strap looped around said axle and connected tautly to the lower end of said coil spring, and a stirrup carried by said lower end of the coil spring in engagement with 65 said strap and acting to maintain the latter out of engagement with said transverse spring.

In witness whereof, I hereto affix my signature.

ELMER E. LYON.
